(57) **CLAIM**

A design for a bottle, as shown and described.

DESCRIPTION

FIG. 1 is a front elevational view of a bottle, the rear elevational view being a mirror image thereof;

FIG. 2 is a right side elevational view thereof;

FIG. 3 is a left side elevational view thereof;

FIG. 4 is a top plan view thereof; and,

FIG. 5 is a bottom plan view thereof.

Portions shown in phantom lines are for illustrative purposes only and form no part of the claimed design.
